PRINTING APPARATUS

George W. Booth, Baltimore, Md., assignor to
 Crown Cork & Seal Company, Inc., Baltimore,
 Md., a corporation of New York

Application August 28, 1935, Serial No. 38,307

18 Claims. (Cl. 101—37)

The present invention relates to apparatus for feeding a line of separate articles such as container closures and printing or otherwise imposing data or decorative matter thereon.

5 A principal object of the invention is to provide means whereby separate preformed articles, such as closures, may be fed and impressed upon with precision.

Another object is to provide means whereby 10 articles having surfaces in different planes may have printed matter accurately imposed on the different surfaces.

As exemplifying the invention I have shown in 15 the accompanying drawings an embodiment designed particularly to feed and print closures having central and marginal portions in different planes, closures of this type being disclosed in my Patent No. 1,956,217 issued April 24, 1934. The apparatus may also include a drying oven 20 to which the printed closures are immediately passed.

In the drawings,

Figure 1 is a front elevation of the machine;

25 Figure 2 is a plan view of the printing section of the machine;

Figure 3 is a plan view of the feeding section of the machine;

Figure 4 is a longitudinal vertical section of the feeding section of the machine;

30 Figure 5 is an enlarged plan view, partly in section, of a portion of the feeding section of the machine;

Figure 6 is a section substantially on line 6—6 of Figure 4;

35 Figure 7 is a section substantially on line 7—7 of Figure 6;

Figure 8 is a section substantially on line 8—8 of Figure 4;

40 Figure 9 is a vertical longitudinal sectional view taken at the extreme right of Figure 3;

Figure 10 is a sectional view substantially on line 10—10 of Figure 2;

Figure 11 is a sectional view substantially on line 11—11 of Figure 10;

45 Figure 12 is a section substantially on line 12—12 of Figure 10;

Figure 13 is an enlarged sectional view taken at the bottom of the right hand roll of Figure 10;

50 Figure 14 is a sectional view taken at the bottom of the left hand roll of Figure 10;

Figure 15 is a partial elevation partly in section of a modified form of printing roll;

55 Figure 16 is a section substantially on line 16—16 of Figure 15;

Figure 17 is a plan view of a printing band appearing in elevation in Figure 15;

Figure 18 is an axial section of a further modified form of printing roll;

5 Figure 19 is an elevation partly in section of the devices of Figure 18 as seen from the left of that figure;

Figure 20 is a plan view of a portion of the printing roll of Figure 18 partly in section on line 20—20 of Figure 18, and

10 Figure 21 is a partial axial section of another modified form of printing roll.

Referring to the drawings, the printing section of the machine comprises a pair of parallel vertical frame members or walls 25 and 26, the member 25, which is at the rear of the machine, having an upward extension 27. These frame members are suitably secured together by cross members so as to provide a rigid supporting structure. At its right hand end, Figure 1, the frame 20 has secured thereto one end of a horizontal table 28 whose other end is supported on legs as at 29.

15 Adjacent the ends of walls 25 and 26 remote from table 28 the walls have journaled therein a shaft 30 on which is fixed a sprocket 31. A bracket 32 secured beneath the table 28 at the outer end of the latter carries a stub shaft 33 on which is journaled a disc 34, this disc carrying a rim sprocket 35 through pin and slot connections, as shown, so that the sprocket is angularly adjustable relative to the disc. While this adjusting feature is not essential for the sprocket 35 since disc 34 is freely rotatable on shaft 33, such an arrangement is preferred for sprocket 31, since the latter should be adjustable relative to shaft 30. An endless sprocket chain 36 connects the two sprockets, the chain being provided at intervals with outwardly projecting fingers 37.

20 For the purpose of tensioning the chain, bracket 32, Figure 9, has a plate base provided with slots through which are passed cap screws as at 38 and 39. A depending flange 40 at the end of table 28 is provided with bores rotatably receiving cap screws as at 41, these being threaded into bores in the bracket base. Upon loosening the screws 38 and 39, the bracket may be adjusted longitudinally of the table by turning the screws 41, screws 38 and 39 being again tightened to hold the bracket in adjusted position.

25 Table 28 has a lower longitudinally extending rib 42, Figure 6, in which is formed an upper, longitudinally extending channel 43 having on 55

the bottom wall thereof a longitudinal rib 44. The upper run of chain 36 is disposed in channel 43, the chain being supported and guided on rib 44, as shown. The side walls of channel 43 are 5 surmounted by longitudinally extending rabbets 45 and 46 in which are set angle strips 47 and 48, a slot existing between the said strips through which fingers 37 project. The distance between the vertical flanges of the angle strips 47 and 48 10 is slightly greater than the diameter of the closures 49. The closures 49 as here shown are discs of the substantially flat form disclosed in my Patent No. 1,956,217, but having a slightly upwardly offset central portion so that the top of 15 the central portion and the top of the marginal portion lie in separate planes.

Mounted in mating recesses as at 50 above channel 43, Figures 5 and 6, are the base flanges of a series of magazines 51 to 57, these magazines being adapted to receive stacks of the closures 49. The magazines are all of identical construction and their ejecting mechanisms are in general the same as disclosed in the Huntley et al. Patent No. 1,956,218, April 24, 1934. The 20 construction is particularly shown in Figures 5 and 6 of the present drawings to which reference 25 will now be made.

The base flange 54' is provided with three 30 equally spaced radial recesses 56 adjacent the inner margins of which are pivoted on vertical pins 57 the finger devices 58, these having the inwardly projecting fish tails with points 59 and 60 which are vertically spaced slightly more than the thickness of the closure margins. A ring 61 35 surmounting flange 55 has a peripheral groove in which is oscillable a ring 62, the latter carrying pins 63 which engage in notches in the outer ends of the devices 58. The pivot pins 57 are mounted in bores in ring 61. Ring 62 has a 40 radially extending lug 64 which carries an upwardly projecting pin 65 on which is mounted a roller 66. A tubular member 67 has a base flange mounted on top of ring 61. Members 54', 61, and 67 have flush cylindrical inner walls whose 45 diameter is slightly greater than the diameter of the closures and the same as the distance between the vertical flanges of angles 47 and 48. The axis of these members intersects the central longitudinal line of channel 43.

50 When a stack of closures is placed in the magazine, the bottom one comes to rest on top of the lower points 59, the upper member normally being outside of the inner circle of flange 55. When ring 62 is turned in a clock-wise direction, 55 Figure 5, the points 60 come above the lowermost closure and the lower points pass outwardly out of engagement with the same so that the latter is ejected downwardly by gravity, the upper points supporting the closures thereabove. As 60 ring 62 is returned, the points 60 recede and permit the stack to drop onto points 59 which have again moved thereunder. In this manner, the closures are ejected one by one onto the track-way 65 constituted by strips 47 and 48.

65 The flange 55 is engaged by clips 68 screw attached to the table top so as to be securely held in position, and if desired, positioning dowels may be located between the flange and the bottom of the recess 50. The recesses 50 are equally spaced apart.

70 The lugs 64 all project toward the rear of the machine and adjacent a longitudinally extending square bar 69 which is slidable on top of table 28 and guided at its ends in brackets 70 and 71. Opposite the magazines, bar 69 carries

72 which have prongs projecting toward the magazines and between which the rolls 66 on pins 65 are engaged. The slides 72 have legs extending across the sides of bar 69, their lower ends being joined by plates as at 73 to hold the slides against lifting. To the left of each slide 72, see Figure 5 in particular, a block 74 is fixed to the top of bar 69. The blocks and slides have opposed recesses in which are engaged the ends of compression springs 75 so that each slide is 10 yielding urged to the left. Each slide 72 has an abutment screw 76 threaded into its right hand side and locked by means of a nut 77. These abutment screws normally engage the blocks 74 15 to the right of their associated slides.

Upon movement of bar 69 to the right, the slides are all carried therewith under the force of springs 75 to cause closure discs to be simultaneously ejected from all of the magazines 51 to 57. However, in case of a jam occurring in 20 one or more of the magazines, the slides 72 may yield so as to avoid breakage. It will be understood that proper positioning of slides 72 relative to their associated magazines is secured through proper adjustment of abutment screws 25 76.

A bracket 78 secured beneath table 28 at the left hand end of rod 69 carries a pin 79 on which is mounted a lever 80 whose upper end extends through an opening in the table and is pivoted by means of a pin 81 to the end of rod 69. Pin 81 is carried in slightly longitudinally elongated openings in the forked end of lever 80 so that the latter is able to swing freely. Journalized in parallel relation to pin 79 in a lower bearing 82 of 30 bracket 78 is a shaft 83. A head 84 on shaft 83 carries a crank pin 85 which is engaged in a longitudinally extending slot 86 in the lower end of lever 80. Through rotation of shaft 83, the proper reciprocating range is imparted to bar 69. 40

The feeding fingers or pins 37 are spaced apart as the centers of the magazines. The speed of chain 36, which is driven by mechanism to be later described, is such relative to the speed of the synchronized shaft 83 that upon the ejection 45 of a group of closures, the next group will not be ejected until the last closure of the preceding group has traveled past magazine 51 and the closure then ejected from magazine 51 will fall in front of the first idle finger 37. The direction 50 of travel of the upper run of the chain is to the left, all views. The timing is such that as the closures are ejected, the feeding fingers come into propelling engagement therewith almost immediately to slide the closures along the track. 55

There is a tendency for the ejected closures to float downwardly rather than to move rapidly onto the track and the consequent retarded movement may be such as to cause the closures to be missed by the proper feeding fingers. In 60 order to overcome this possible difficulty, I provide means for exhausting the air beneath the ejected closures.

Beneath each magazine the guide rails 47 and 65 48 and rib 42 are provided with through ducts or passages 87 and 88, Figures 4 to 7. A trough-like member 89 is secured beneath rib 42 and closes the lower ends of all of the passages 87 and 88 to provide a manifold in conjunction with the lower surface of the rib. Member 89 has a 70 central sump 90 whose rear side wall has an opening 91, this side wall being expanded into a flange 92 against the outer face of which is secured the flange 93 of a valve housing 94. Valve housing 94 has an opening 95 aligned with the 75

opening 91, Figures 6 and 7, and includes a counterbore 96 intersecting opening 95. Counterbore 96 is closed at one end by a threaded cap 97 and receives a valve plunger having a head 98 pressed against a seat 99 by means of a compression spring 100 interposed between the head and the cap. The plunger has a reduced stem portion 101 and a cylindrical enlargement 102 slidably in the reduced end of the counterbore beyond seat 99. A port 103 communicating with counterbore 96 opposite the stem portion 101 is outwardly flanged for connection with a pipe 104, this latter leading from any suitable suction device such as a pump or reservoir. An abutment screw 105 is threaded into the outer extremity of enlargement 102 and locked by means of a nut 106.

An arm 107 secured to the underside of bar 69 projects downwardly through a slot in table 28 with its lower end in front of abutment screw 105. As bar 69 moves to the right to cause closures to be ejected, it strikes abutment screw 105, unseating the valve head 98 and connecting the passages 87 and 88 with the vacuum device, this connection occurring substantially at the moment the closures are released by the fish tail points. Since the orifices of passages 87 and 88 immediately underlie the marginal portions of the closures, the latter are instantaneously drawn downwardly onto the guide rails. Arm 107 strikes abutment screw 105 only near the end of the right hand travel of bar 69, that is, when the latter has moved far enough to effect ejection. As bar 69 almost immediately starts to return, the valve head 98 is immediately seated by its spring so that suction is interrupted slightly before the closures are engaged by the feeding fingers, thus eliminating drag on the latter.

As the propelled caps pass to the printing section of the machine, they are received on track sections 110, 111, 112, and 113, Figure 2. Each of these track sections comprises an upwardly faced channel base, forming a continuation of channel 43, and pairs of guide rails as at 114 and 115, Figure 12. In order that the closure discs may be prevented from lifting, the shoulders of the rails 114 and 115 may have applied to their tops strips 116 and 117 whose adjacent marginal portions overhang the edges of the discs. The track section 110 is secured to the adjacent end of section 111 for support thereby. Sections 111 and 112 constitute platens for co-operation with printing rolls 118 and 119 and are supported between the side walls 25 and 26 for vertical adjustment by means to be later described. The track section 113 is fixedly supported by means of cross bars as at 120. The left hand end of section 113 projects beyond sprocket 31 and is longitudinally slotted to permit chain 26 to pass around the sprocket.

A pulley 121, Figure 1, mounted on a stud 122 at the rear side of wall 25, is connected to any suitable prime mover by means of a belt 123. The pulley has fixed thereto a gear 124 which meshes with a gear 125 fixed on the sprocket shaft 30. Gear 125 meshes with an idler 126 mounted on a stud at the rear of wall 25, the idler driving a similarly mounted gear 127. Gear 127 meshes with gears 128 and 129 fixed on shafts 130 and 131, Figures 10 and 11, which carry the printing rolls, the shafts 130 and 131 being journaled in bushings as at 132, Figure 11, fixed in wall 25. A sprocket 133 fixed to gear 127 is connected by means of a chain 134 with a sprocket 135 fixed on shaft 83, a tension roller

136, as here shown, engaging the top run of chain 134. Since shaft 83 is in connection with the roll driving gears 118 and 119 through gear 127, sprockets 133 and 135 and chain 134, and since gear 127 is driven through idler 126 which engages gear 125 fixed on the drive shaft for the conveyor chain, it will be evident that the speed of rotation of the printing rolls, the speed of chain 26, and the reciprocating period of rod 69 will bear a constant relation.

The frame extension 27 carries series 137 and 138 of inking rolls, the top rollers of the series being in communication with reservoirs 139 and 140. Since the inking mechanism may be of conventional form, no detailed description is required at this time. The rollers may be driven from gears 128 and 129.

Drying mechanism for the printed closures may be provided for use where required. To this end a shaft 141 at the left hand end of the main frame and journaled in the walls thereof has fixed thereon a sprocket 142 engaged by a chain 143 whose upper run, guided over an idler 144, transverses a drying oven 145. Chain 143 has outwardly projecting fingers thereon between 25 which closures passing from the adjacent extremity of track section 113 are adapted to fall. A sprocket 146 free on the forward end of shaft 141 is connected by a chain 147 with a sprocket 148 fixed on shaft 30. A disc 149 keyed on shaft 141 may be engaged or disengaged with sprocket 146 by means of a clutch pin 150. With the clutch pin engaged, the conveyor chain 143 is continuously driven from shaft 30, or by releasing the pin, the drive may be disconnected. Since it is sometimes desired to drive the drying conveyor without operating the rest of the machine, I preferably provide an independent drive therefor, this being operable when the clutch pin 150 is withdrawn to free disc 149 from sprocket 146. In Figures 1 and 2 I have shown a drive chain 151 connecting any suitable source of power with a sprocket 152 loose on shaft 141. On its inner face the sprocket has a clutch collar 153 secured thereto and engageable by a clutch collar 154 which is splined on shaft 141. A shipper fork 155 operatively associated with clutch collar 154 is manipulatable by means of a lever 156 to slide collar 154 along shaft 141 between clutch engaging and disengaging positions. The clutch 153, 154 is only engaged when it is desired to drive the drying conveyor independently of the rest of the machine, and in this circumstance, disc 149 and sprocket 146 will be disengaged, as above mentioned, so that drive will not be communicated to shaft 30.

Track section 111, Figures 2, 10, and 12, has a pair of transverse bores in which are rockably received eccentric bushings 157 and 158 fixed on shafts 159 and 160 which are journaled in walls 25 and 26. Between shafts 159 and 160 on the front face of wall 26 a pair of brackets 161 and 162 are fixed, these providing journals for a spindle 163 which has an enlargement between the two brackets to prevent endwise displacement of the spindle. The ends of the spindle project beyond the brackets and are provided with worms 164 and 165 which engage small worm wheels 166 and 167 fixed on the ends of shafts 159 and 160.

The eccentrics 157 and 158 occupy the same angular positions relative to their axes and, upon turning spindle 163, are similarly rocked by their supporting shafts to move track section 111 translationally toward or away from printing roller 118 for efficient cooperation with the lat-

ter as a platen. The worms and worm wheels are self-locking so that the platen is rigidly held in adjusted position. The enlarged portion of the spindle may be provided with openings as at 168, 5 if desired, so as to be engageable by a pin or the like for turning.

Platen 112 is supported and adjustable in exactly the same manner as platen 111, its supporting shafts being designated at 169 and 170 10 and the eccentrics at 171 and 172, Figure 10.

The two platens are independently adjustable, as will be evident. Due to the action of the eccentrics, the platens upon adjustment will undergo longitudinal as well as vertical movement 15 and, for this reason, a small space is left between the platens as well as between track section 113 on the one hand and section 110 and table 28 on the other hand. The right hand ends of the chain guiding ribs and of the guide rails 114 and 20 115 of sections 110, 112, and 113 may be slightly beveled off to provide a smooth track when their top faces are adjusted out of flush relation.

As herein contemplated, printing roll 118 is designed to print on the raised central portion 25 of the closures and printing roll 119 on the depressed annular portions. Except for the printing pads used, the two rolls are otherwise identical and the following description directed to roll 118 will be understood to apply also to roll 119.

Referring particularly to Figures 1, 10, 11, 12, 30 and 13 of the drawings, roll 118 comprises a cylindrical core member 173, an intermediate ring portion 174 and an outer ring portion 175. The core 173 is keyed on shaft 130 and held against outward axial movement by a washer 176 secured to 35 the end of the shaft. At its outer end the core has a flange 177 expanded at diametrically opposite points to provide lugs 178 and 179 which lie against the outer face of ring portion 174. Lug 40 179 has a transverse slot through which is passed the shank of a screw 180 threaded in a tapped aperture in the ring. Lug 178 projects between a pair of split lugs 181 and 182 projecting outwardly from ring 174, these latter carrying screws 183 45 and 184 whose adjacent ends bear against lug 178. Ring 174 may be turned relative to core 173 upon loosening screw 180 and adjusting screws 183 and 184. In this manner, the required angular adjustment of the ring and core may be 50 effected, screws 183 and 184 locked in abutment with lug 187, and screw 180 tightened to hold ring 174 against lug 179.

At its rear edge, ring 174 has an annular shoulder 185 abutted by ring 175, the two rings being 55 keyed together as indicated in Figure 12. In radial grooves 186 and 187 formed in the bottoms of channels 188 and 189 on the front face of ring 174 are disposed a pair of lugs 190 and 191, these lugs being secured to the ring by means of screws 60 192 and 193. The outer ends of lugs 190 and 191 overlap the inner portion of ring 175 to secure the latter against shoulder 185.

The side faces of ring 175 are provided with annular grooves 194 and 195. Disposed about the 65 periphery of ring 175 in equally spaced relation are a series of printing pads 196 which may be conveniently formed of rubber although any other suitable material may be used. Each pad 196 has a printing area for cooperation with the central 70 portions of the closures. Each pad is secured as by an adhesive to an arcuate base plate 197 whose curvature is that of ring 175. The lateral edges of each base plate 197 are beveled and engaged by the beveled ends of substantially U-shaped clamps 198 and 199 having legs engaged in grooves 75

194 and 195, Figure 12, the bridge portions of the clamps being ordinarily somewhat spaced from the sides of the ring as indicated. The clamps are secured to ring 175 by means of screws 200 and 201. It will be evident that upon loosening the screws, the base plates may be slid circumferentially of ring 175 and may also be adjusted transversely thereof by proper adjustment of the screws. In Figure 12, for example, the base plate 197 is shown as being adjusted slightly to the 10 right relative to ring 175 for the purpose of securing proper register. If necessary, shims may be interposed between the base plate and ring 175 to insure uniform printing of the pads.

In Figure 14, in particular, the base plate 197, 15 secured to roll 119, is shown as having affixed thereto a printing pad 202 having an annular printing face 203 of a size to engage and print the marginal portions of the closures. The central portion of pad 202 is spaced above the upwardly offset central portion of the closure so as to prevent smearing of the printing previously effected by a pad 196.

The printing pads are spaced apart on their respective rolls at intervals corresponding exactly to the spacing of the closures as fed under the rolls by fingers 37 and the relative adjustment of the chain and rolls is such as to bring successive discs into exact printing register with successive pads. The peripheral speed of the rolls 30 is exactly the same as the speed of the chain. Clearance is provided between the pads for the upper extremities of the feeding fingers 37.

The closures may be simple metal plates or 35 may be of laminated construction. Where the printing surfaces are metal, the drying oven is ordinarily required but with the printing surfaces faced with paper, for example, which will absorb the ink, the oven can be dispensed with.

Due to the various adjustments which have 40 been described and the interconnection of all of the driven mechanisms, the closures may be accurately fed to the chain and accurately presented to the printing rolls and the machine operated at a satisfactory production speed.

In the described machine, two rolls are provided for printing on different surfaces of a closure or the like. If it were desired to print only on one surface or if the closure were uni-planar, one roll could of course be dispensed with. The 50 principal purpose of providing the two rolls is to avoid the difficulty of inking a printing pad having printing surfaces at different levels. However, with the single roll, a printing roller may be provided for inking the outer level of a plural level pad and a further roller for inking the lower level. The latter roller would be provided with localized inking pads moved in timed relation with the printing roll so that successive 60 inking pads would cooperate with successive printing pads. In the present case, if pads 196 and 202 were combined, a plane cylindrical inking roller could be provided for the outer annular printing portion 203 and a cylindrical roller with raised inking pads for cooperation with 65 pads 196.

The printing rolls may be designed to carry a circular band on which the pads are properly spaced. In Figures 15 and 16, a roll 204 is shown as carrying a continuous band 205 on 70 which are affixed at proper intervals the printing pads 206, the band and pads being shown in plan in Figure 17. At its ends, the band has affixed thereto wedge-shaped blocks 207 and 208, these being received in a groove 209 extending 75

transversely of the roll periphery. A transverse rib 210 in groove 209 and integral with the roll lies between blocks 207 and 208. A U-shaped locking member 211 having legs 212 and 213 with wedge faces for engagement with blocks 207 and 208 is pulled into engagement with the latter by means of a screw 214 threaded in the end of rib 210 for the purpose of tensioning the band. Blocks 207 and 208 are undercut as shown in Figure 15 so that the ends of the band are held down. The ends of blocks 207 and 208 opposite screw 214 abut an annular shoulder 215 on the roll to prevent their transverse displacement under the action of member 211. The advantage of this arrangement over the previously described is that the pads may be accurately placed on the band and the whole group applied to the roll in a single operation.

In Figures 18 to 20, I have shown means for moving an inner printing pad relative to an outer pad so that the two may be at different levels for printing but at the same level for inking. In these views, the ring 216 is provided in its side toward wall 25 with an annular groove 217. Peripherally, the roll is provided with a series of circular radial recesses 218 having central cylindrical radial bosses 219 therein. Cup-shaped plungers 220 are positioned in recesses 218 and as shown in Figure 20 have flanges 220' provided with radial projections as at 221 and 222 mating with similarly shaped axially extending recesses in the walls of the recesses to prevent turning of the members 220. On their outer circular faces, members 220 carry printing pads 222 which are radially movable in openings in a printing pad 224 and its base plate 225, the latter being secured to the roll by means of screws 226. Interposed between plates 225 and the flanges 220' are compression springs 225 which tend to move members 220 inwardly. Each member 220 has secured thereto a cylindrical stem 226 slideable in a radial bore in a boss 219.

Secured to wall 25 and projecting within recess 217 are upper and lower substantially semi-cylindrical cam members 227 and 228 and the latter, if desired, may be rendered somewhat vertically adjustable by the illustrated screw and slot connection between its flange 229 and wall 25. Cam 227 is formed on a somewhat greater radius than cam 228 and has end portions 230 overlying the ends of the latter in the manner shown in Figure 19 to provide a smooth peripheral track. The inner ends of stems 226 bear against cams 227 and 228 by reason of the action of springs 225. When any stem is on cam 228, its associated pad 223 is projected outwardly to the level of the printing portion of pad 224 so that the two pads may be simultaneously inked. When a stem 226 is on cam 228, its associated pad 223 is retracted by the spring 225 to the position shown in Figure 18 so as to print properly on the raised surface of the closure while the other pad is printing the closure margin. Vent openings 218a and 218b are provided for recess 218 to eliminate dash pot effects.

In Figure 21, a somewhat similar arrangement to that described is shown. In this figure, the roll 231 is provided with radial bores 232 in which are slideable cylindrical cup-shaped plungers 233 which carry printing pads 234, these latter being movable within the outer pads 235. Members 233 are pressed outwardly by means of compression springs 236, movements of members 233 being limited by means of screws 237 passed through the walls of bores 232 and en-

gaged in axially extending ended recesses in members 233. A vent duct is shown at 238.

Springs 236 normally hold pads 234 at the level of pads 235 for inking, the pads 234 being unable to pass this position due to the limiting effect of screws 237. During the printing operation, however, the raised portions of the closures push the pads 234 inwardly to the position shown so that both levels of the cap are simultaneously printed upon.

It will be understood that the specific disclosure herein may be departed from without departure from the scope of the invention. Variations are possible in the form and arrangement of parts, and accordingly, I do not limit myself except as in the following claims:

I claim:—

1. Apparatus of the class described comprising a horizontal track, a magazine disposed above said track and containing a stack of closures, means for ejecting the closures one by one from the bottom of the stack, and a suction line including an orifice beneath the ejected closure for drawing the same onto the track.

2. Apparatus of the class described comprising a horizontal track, a magazine disposed above said track and containing a stack of closures, means for ejecting the closures one by one from the bottom of the stack, a suction line including an orifice beneath the ejected closure for drawing the same onto the track, a valve normally closing said line, and means for opening said valve as each closure is ejected.

3. Apparatus of the class described comprising a horizontal track having a central longitudinally extending slot, conveying means extending upwardly through said slot, a magazine disposed above said track and containing a stack of closures, means for ejecting the closures one by one from the bottom of the stack, and a suction line including orifices in the track at the sides of said slot and beneath the ejected closure for drawing the same onto the track.

4. Apparatus of the class described comprising a horizontal track having a central longitudinally extending slot, conveying means extending upwardly through said slot, a magazine disposed above said track and containing a stack of closures, means for ejecting the closures one by one from the bottom of the stack, a suction line including orifices in the track at the sides of said slot and beneath the ejected closure for drawing the same onto the track, a valve normally closing said line, and means for opening said line as each closure is ejected.

5. Apparatus of the class described comprising a horizontal track having a central longitudinally extending slot, an endless draft device having a run underlying said slot, feeding fingers spaced along said run and projecting upwardly through said slot, a magazine positioned above said slot and containing a stack of closures, means for ejecting closures one by one from the bottom of said stack to be engaged and propelled by said fingers, a suction line including orifices beneath the ejected closure for drawing the same onto the track, a valve in said line, and means for opening said valve as each closure is ejected and for closing the valve just prior to the engagement of the closure by a feeding finger.

6. Apparatus for printing closure discs of the type having marginal portions and central portions in separate planes, comprising a pair of printing rolls in tandem relation, one of said

rolls having localized printing portions spaced circumferentially thereon for printing on the marginal portions of the discs and the other having similarly spaced localized printing portions 5 for printing on the central portions of the discs, means for driving the rolls at the same peripheral speed and means for feeding the discs in line beneath said rolls with the discs spaced apart as said printing portions and at a speed equal to 10 the peripheral speed of said rolls whereby the marginal and central portions of the discs are successively printed upon by the printing portions of the rolls.

7. Apparatus of the class described comprising a printing roll having raised printing pads circumferentially spaced thereon, means for driving the roll, a platen for cooperation with said roll and having a longitudinal slot, and propelling means for closures to be printed comprising feeding fingers projecting upwardly through said slot above the edge of the propelled closure, said propelling means being timed to feed the closures under the pads to be printed upon as said roll is driven, the upper ends of 25 said fingers having clearance between the pads.

8. Apparatus for printing closure discs of the type having high and low portions, said apparatus comprising rotary means, a pair of printing members carried by said rotary means, a rectilinearly extending platen for supporting the discs to be printed, one of said printing members having a path elevated with respect to the platen as compared to the path of the other so that the first is adapted to print on the high portions 30 of the discs and the other is adapted to print on the low portions of the discs, and means for propelling the discs in equally spaced relation along said platen at a speed equal to the peripheral speed of said rotary means.

40 9. Apparatus for printing closure discs of the type having high and low portions, said apparatus comprising rotary means, a pair of printing members carried by said rotary means, a rectilinearly extending platen for supporting the discs to be printed, one of said printing members having a path elevated with respect to the platen as compared to the path of the other so that the first is adapted to print on the high portions 45 of the discs and the other is adapted to print on the low portions of the discs, the printing action of said members being successive, and means for propelling the discs in equally spaced relation along said platen at a speed equal to the peripheral speed of said rotary means.

55 10. Apparatus for printing closure discs of the type having high and low portions, said apparatus comprising rotary means, a pair of printing members carried by said rotary means, a rectilinearly extending platen for supporting the discs to be 60 printed, one of said printing members having a path elevated with respect to the platen as compared to the path of the other so that the first is adapted to print on the high portions of the discs and the other is adapted to print on the low 65 portions of the discs, said rotary means comprising a pair of rolls, one of the rolls carrying one of the printing members and the other roll carrying the other printing member, means for driving the rolls at equal peripheral speed, and means 70 for propelling the discs in equally spaced relation along said platen at a speed equal to the peripheral speed of the rolls.

11. Apparatus for printing closure discs of the type having high and low portions, said apparatus comprising rotary means, a pair of printing

members carried by said rotary means, a rectilinearly extending platen for supporting the discs to be printed, one of said printing members having a path elevated with respect to the platen as compared to the path of the other so that the first 5 is adapted to print on the high portions of the discs and the other is adapted to print on the low portions of the discs, the printing action of said means being substantially simultaneous, and means for propelling the discs in equally spaced 10 relation along said platen at a speed equal to the peripheral speed of said rotary means.

12. Apparatus for printing closure discs of the type having high and low portions, said apparatus comprising rotary means, a pair of printing 15 members carried by said rotary means, a rectilinearly extending platen for supporting the discs to be printed, one of said printing members having a path elevated with respect to the platen as compared to the path of the other so that the first 20 is adapted to print on the high portions of the discs and the other is adapted to print on the low portions of the discs, one of said printing members being surrounded by the other, and means for propelling the discs in equally spaced 25 relation along said platen at a speed equal to the peripheral speed of said rotary means.

13. Apparatus for printing closure discs of the type having high and low portions, said apparatus comprising rotary means, a pair of printing 30 members carried by said rotary means, a rectilinearly extending platen for supporting the discs to be printed, one of said printing members having a path elevated with respect to the platen as compared to the path of the other so that the first 35 is adapted to print on the high portions of the discs and the other is adapted to print on the low portions of the discs, one of said members being radially movable relative to the other, and means for propelling the discs in equally spaced 40 relation along said platen at a speed equal to the peripheral speed of said rotary means.

14. Apparatus for printing closure discs of the type having high and low portions, said apparatus comprising rotary means, a pair of printing members carried by said rotary means, a rectilinearly extending platen for supporting the discs to be printed, one of said printing members having a path elevated with respect to the platen as compared to the path of the other so that the first is adapted to print on the high portions of the 45 discs and the other is adapted to print on the low portions of the discs, one of said members being radially movable relative to the other, means for projecting the movable member from a relatively retracted printing position to an inking position 50 wherein it is substantially flush with the other member, and means for propelling the discs in equally spaced relation along said platen at a speed equal to the peripheral speed of said rotary 55 means.

15. Apparatus for printing closure discs of the type having high and low portions, said apparatus comprising rotary means, a pair of printing members carried by said rotary means, a rectilinearly 60 extending platen for supporting the discs to be elevated with respect to the platen as compared to the path of the other so that the first is adapted to print on the high portions of the discs and the other is adapted to print on the low 65 portions of the discs, one of said members being radially movable relative to the other, means for projecting the movable member from a relatively retracted printing position to an inking position 70 wherein it is substantially flush with the other 75 member.

member, means for retracting said movable member, and means for propelling the discs in equally spaced relation along said platen at a speed equal to the peripheral speed of said rotary means.

5 16. Apparatus for printing closure discs of the type having high and low portions, said apparatus comprising rotary means, a pair of printing members carried by said rotary means, a rectilinearly extending platen for supporting the discs to be printed, one of said printing members having a path elevated with respect to the platen as compared to the path of the other so that the first is adapted to print on the high portions of the discs and the other is adapted to print on the low portions of the discs, one of said members being 10 radially movable relative to the other, means for moving the movable member from an inking position wherein it is substantially flush with the other member to a relatively retracted printing position, and means for propelling the discs in equally spaced relation along said platen at a speed equal to the peripheral speed of said rotary means.

15 17. Apparatus for printing closure discs of the type having high and low portions, said apparatus comprising rotary means, a pair of printing members carried by said rotary means, a rectilinearly extending platen for supporting the discs to be printed, said platen comprising separate 20 portions respectively cooperable with the rolls,

the platen portions being adjustable independently of each other relative to their associated rolls, one of said printing members having a path elevated with respect to the platen as compared to the path of the other so that the first is adapted to print on the high portions of the discs and the other is adapted to print on the low portions of the discs, said rotary means comprising a pair of rolls, one of the rolls carrying one of the printing members and the other roll carrying the other printing member, means for driving the rolls at equal peripheral speed, and means for propelling the discs in equally spaced relation along said platen at a speed equal to the peripheral speed of the rolls.

18. Apparatus of the class described comprising horizontally extending conveying mechanism, means for driving said conveying mechanism, a group of magazines disposed above said conveying mechanism in equally spaced relation and containing stacks of closures, means for intermittently ejecting closures from all said magazines onto said conveying mechanism, and operating means for said last named means intermittently driven from said driving means and so timed that the first of one series of ejected closures is spaced from the last of the preceding series a distance the same as the spacing of the closures of each series.

GEORGE W. BOOTH.
